BOTTLE

Emory L. Groff, Jr., 6308 Redwig Road, Bethesda, Md.

Filed Aug. 7, 1964, Ser. No. 81,203

Term of patent 14 years

(Cl. D58—5)

FIG. 1.

FIG. 2.

FIG. 3.

FIG. 7.

FIG. 4.

FIG. 5.

FIG. 6.

FIG. 1 is a perspective view of the bottle showing my new design.

FIG. 2 is another perspective view thereof, taken from the left-hand side of FIG. 1.

FIG. 3 is a top plan view thereof.

FIG. 4 is an end elevational view taken from the right-hand side of FIG. 2.

FIG. 5 is a side elevational view thereof.

FIG. 6 is an end elevational view thereof, taken from the right-hand side of FIG. 1.

FIG. 7 is a horizontal cross-section taken on the line 7—7 of FIG. 5.

I claim:

The ornamental design for a bottle, substantially as shown.
